United States Patent Office.

CHARLES EISELE, OF NEWARK, NEW JERSEY.

Design No. 3,952, dated April 5, 1870.

DESIGN FOR HARNESS-MOUNTINGS.

The Schedule referred to in these Letters Patent and making part of the same.

To all whom it may concern:

Be it known that I, CHARLES EISELE, of Newark, in the county of Essex and State of New Jersey, have invented a new Design for a Set of Harness-Mountings, of which the following is a specification.

The characteristic of my design is that all the bows, rings, loops, hooks, and eyes of the harness have the form of an inverted lyre; and I therefore call the mountings made according to my design, the "Lyre" mountings.

The design is fully represented in the accompanying photographic illustration which forms part of this specification, in which—

Figure 1 is the martingale-ring.

Figure 2 is the pad-hook.

Figure 3 is the union-hook.

Figure 4 is the post-hook.

Figure 5 is the breeching-ring.

Figure 6 is the terret.

Figure 7 is the fly-terret.

Figure 8 is the hame-terret.

Figure 9 is the buckle.

Figure 10 is the crupper-loop.

Figure 11 is the gag-swivel.

Figure 12 is the hook and eye.

What I claim as my invention, and desire to secure by Letters Patent, is—

The design for a set of harness-mountings herein described and represented.

CHARLES EISELE.
